UNITED STATES PATENT OFFICE.

HENRY W. PLEISTER, OF WESTFIELD, NEW JERSEY, ASSIGNOR TO HENRY B. NEWHALL.

BOLT-ANCHOR.

1,267,901.

Specification of Letters Patent. Patented May 28, 1918.

Original application filed September 20, 1916, Serial No. 121,105. Divided and this application filed September 18, 1917. Serial No. 191,918.

To all whom it may concern:

Be it known that I, HENRY W. PLEISTER, a citizen of the United States, residing at Westfield, in the county of Union and State of New Jersey, have invented certain new and useful Improvements in Bolt-Anchors, of which the following is a specification, taken in connection with the accompanying drawings.

10 This application is a division of my co-pending application, Ser. No. 121,105, filed September 20, 1916.

My invention relates to bolt anchors and more particularly to a bolt anchor which has 15 a great holding capacity and yet one which will not crack a wall, a partition, a block of marble, stone or any other material in which it may be desired to use my bolt anchor.

The common form of bolt anchors are expanded by having the expanding member, the screw or bolt, move down an inclined surface which extends approximately from one end to the other, and which reaches its nearest approach to the axis of the bolt 25 anchor at the end which is farthest embedded in the wall, block or other material. This causes the maximum expansion to be at the very end of the bolt anchor. This makes it impossible to use the ordinary common 30 form of expansion bolt in many locations.

My expansion bolt removes the point of maximum expansion from the end of the bolt and insures a gradually lessening grip and wedging action from that point to the end 35 of the bolt anchor.

My invention further relates to certain details of construction which will be described in the specification and pointed out in the claims.

40 I have shown in the accompanying drawings an illustrative embodiment of my invention but of course it is to be understood that my invention is not to be confined simply to the form illustrated. In these drawings 45 the same reference numerals refer to similar parts.

Figure 1 is a longitudinal vertical section of my invention shown as a one part lag shield having an open side permitting the 50 lag screw to engage directly both with the lag shield and the support;

Fig. 2 is a longitudinal vertical section of the lag shield shown in Fig. 1 mounted in a

support and holding the work which is also shown in section.

55 In the illustrative embodiment of my invention 1 is a bolt anchor formed as a one part lag shield 2 having an open side 3, lugs 4, 4, inclined surface 5 which tapers to a point intermediate its ends as for example 60 to the point 6 and then recedes to the point 7 forming the flaring surface 26. Screw threads 8, 8 are preferably cast in the lag shield. I preferably also provide the lag shield with an open unthreaded throat 9, 65 and with longitudinally extending ribs 10 and transverse ribs 11, 11. Of course these ribs may be omitted if desired. The lugs 4, 4 are adapted to connect the shield with the expanding device which in the drawing is 70 shown as a lag screw 21.

It is well known that in thin masonry walls or thin partitions 12, which have the strength to support the work 13 of a given weight, that it is impossible to use a bolt 75 anchor satisfactorily because the wall or partition 12 is relatively so thin, that their use will crack or destroy the surface 14 of the wall or partition, thereby giving an unsightly appearance to the wall, if not actually 80 requiring the services of a mason or plasterer to touch it up or repair it.

By my invention I avoid the cracking, or marring, or breaking, the wall or support 12 by removing the maximum strain and wedging stresses from the point 15 to a point removed from the end 16 of the bolt anchor and far enough away from the surface 14 so as to bring the point of maximum expansion at substantially the point 17, well within the 90 body of the wall or partition 12.

85 In the operation of my invention, Fig. 2, the hole 18 is formed in the wall or partition 12 leaving a comparatively thin portion 19. The bolt anchor 2 is then inserted and 95 the work 13, whatever its weight may be, will be held to the face 20 of the wall or partition 12 by means of the lag screw 21 which will coöperate with the screw threads 8, 8 on the inclined surface 5 and the flaring 100 surface 26 and, at the same time, the male threads 24 of the lag screw 21 will coöperate directly with the wall or support 12 and cut or form female threads or recesses in the surface 25 of the hole 18. This will cause 105 the lag shield 2 exert the maximum pressure

- at substantially the point 17, well within the wall or partition and removed from the thin portion 19; from the point 17 to the end 16 of the bolt anchor the gripping action will gradually lessen so that at the very end 16 of the bolt anchor, no such strains will be exerted which would cause the fracture or marring of the face 14 of the wall or support 12.
- 10 In the drawing the inclined surface 5 and flaring surface 26 are somewhat exaggerated, as well as the gripping action of the bolt anchor, for purposes of clearer illustration.
- 15 It is also apparent that different thicknesses of work can be held by the same bolt anchor without the lag screw 21 binding before it has snugly secured the work to the face of the wall, partition, block or other support.

Having thus described this invention in connection with an illustrative embodiment thereof to the details of which I do not desire to be limited, except as required by the 25 scope of the appended claims, what is claimed as new and what is desired to secure by Letters Patent is set forth in the appended claims.

What I claim as my invention and desire 30 to secure by Letters Patent is:—

1. An article of manufacture comprising a one part lag shield having an open side and provided with an inner inclined expanding surface inclined from near its outer end 35 to a point intermediate its ends and from that point reversely inclined to the inner end of the lag shield.

2. An article of manufacture comprising a one part lag shield having an inner inclined expanding surface inclined from near its outer end to a point intermediate its ends and from that point reversely in-

clined to the inner end of the lag shield and one or more lugs adapted to connect said shield with a coöperating expanding device. 45

3. An article of manufacture comprising a one part lag shield having an open side and provided with an inner inclined expanding surface inclined from near its outer end to a point intermediate its ends and 50 from that point reversely inclined to the inner end of the lag shield and one or more lugs adapted to connect said shield with a coöperating expanding device.

4. The combination in a bolt anchor of a 55 one part lag shield having an open side and provided with an inclined bore, from near its outer end to a point intermediate its ends, and from that point reversely inclined to the inner end of the lag shield, and an 60 expanding device adapted to coöperate with said inclined surfaces and directly with a support.

5. The combination in a bolt anchor of a 65 one part lag shield having an open side and provided with an inclined bore from near its outer end to a point intermediate its ends, and from that point reversely inclined to the inner end of the lag shield, and a bolt or 70 screw adapted to coöperate with said inclined surfaces and directly with a support. 70

6. An article of manufacture comprising a one part lag shield provided with an inclined bore having interrupted screw threads for a part of its length and a bolt or screw 75 to coöperate with the interrupted screw threads, said inclined bore diminishing in diameter to a point intermediate its ends and from that point increasing in diameter as it advances toward the other end of the shield. 80
